CLOSURE

Charles M. Villanyi, Bayside, N. Y., assignor to
 L. Mundet & Son, Inc., New York, N. Y., a corporation of New York

Application March 21, 1931, Serial No. 524,228

2 Claims. (Cl. 215—48)

This invention relates to a functionally and structurally improved closure.

It is an object of the invention to provide an article of this character capable of use in numerous associations, but primarily intended for the purpose of sealing vessels such as for example, bottles, and by means of which the contents thereof will be effectively prevented from escaping by evaporation or otherwise.

10 Another object of the invention is that of providing a closure which may be unseated with minimum effort and which closure will, despite severe stress, have its component parts remain in properly assembled condition.

15 Another object of the invention is that of providing a closure which may have associated with it a swab and the construction of which closure will be such that the swab will remain as a unit thereof throughout the entire life 20 of the article.

An additional object is that of providing a closure, the construction of which will be relatively simple so that the device may be manufactured to the greatest extent by automatic 25 machinery. Moreover, this device will embody rugged characteristics so that maximum life will be incorporated within the same.

With these and other objects in mind, reference is had to the attached set of drawings illustrating practical embodiments of the invention and in which

Fig. 1 is a sectional side view of a closure applied to a receptacle;

Fig. 2 is a slightly different form thereof; 35 Fig. 3 is a sectional plan view taken along the lines 3—3 and in the direction of the arrows of Fig. 2;

Fig. 4 is a side elevation of the unit as shown in Fig. 1;

40 Fig. 5 is a view similar to Fig. 1 showing a still further form of construction which may be employed, and

Figs. 6 and 7 illustrate additional structures which may be included within the teachings of 45 the present invention.

While a closure constructed in accordance with the present invention may be manufactured of many different materials, it is preferred that it be formed of a moldable material such as 50 "bakelite", or other phenol product. Such materials lend themselves especially to the construction of closures which should be moisture and air-proof and are to be capable of withstanding rough usage.

55 Thus, referring primarily to Fig. 1, the nu-

meral 10 indicates a closure formed of a disk-like body having a downwardly extending flange 11 adjacent its outer edge and the exterior face of which, as in Fig. 4, may be serrated to provide a roughened surface 12 by means of which the cap may be readily gripped and manipulated. The area of this cap should, in the embodiment under consideration, be adequate to insure that the pouring lip of the bottle is enclosed within the flange. The latter 10 is concentrically disposed with respect to a second flange 13 which defines the space within which the plug or stopper 14 is to be disposed. This second flange has a radius such that it lies within the neck of the bottle and it will 15 consequently be appreciated that the entire lip of the receptacle is thus effectively protected.

With a view to securing the stopper to the cap it is preferred, according to the present invention, that a series of spaced annular grooves 20 15 be formed in the inner cap face to provide trough portions within which cement or similar material may be keyed for the purpose of preventing a dislodgment of the stopper or plug 14.

Obviously, the latter may be formed of any 25 desired material as, for example, cork and with the construction aforesaid it will be observed that not alone is the pouring neck of the bottle protected adequately, but also that it is possible to secure a major purchase on the outside of 30 the flange in order forcibly to dislodge the cap and plug from association with the bottle, and the plug or stopper will remain coupled to the cap even under most strenuous conditions of 35 use.

With a view to assisting the withdrawal and insertion of the plug or stopper, it is preferred that the latter as in Fig. 1 be formed with a bore 16 which will break the vacuum or pressure except under final stages of sealing or initial 40 stages of withdrawal. The same results may be achieved by, for example, forming a groove 17 in the side wall of the plug or stopper.

Closures of this nature are quite often employed in connection with a receptacle, the contents of which require the use of a swab. Considerable difficulty has been experienced in securing such an element against accidental displacement. In order to overcome this objection, it is proposed, when necessary, to apply an element of this nature to the closure that the cap of the latter be extended as at 18 in Fig. 2 and that the plug be correspondingly recessed to accommodate this extension. Such a construction would obviously permit of the plug being 55

even more firmly associated with the cap and by having the extension formed with a bore at the time of manufacture, it is feasible to force the end of a rod 19 snugly into this bore after 5 passing through an aligned bore formed in the plug body. It will be found that with such a construction the likelihood of the rod being accidentally detached is precluded and with a view to preventing any detachment of the swab 20 10 from the rod the end of the rod may be split and passed to extend through the fibrous body of the former as has been indicated in Figs. 2 and 3.

The teachings of the present invention and 15 more especially the coupling of the rod to the cap are not limited to the construction shown in Figs. 1 and 2. For example, the cap 21, as shown in Fig. 5, may have a bored extension 26 for the purpose of accommodating the rod 19. 20 Where this construction is resorted to, it is obvious that a relatively deep groove is provided for the reception of a cement or similar material to retain the plug applied to the cap. As indicated in dotted lines, a complementary extension 25 27 might extend from the upper surface of the cap in order to assist in manipulating the same. Also, if desired, the rod as at 28 in Fig. 7 might be molded integrally out of the cap material. However, due to the liability of 30 breakage it is usually preferred that the rod be a unit or element separate from the cap.

As at 29 in Fig. 6, a cap of the general type shown in Fig. 5 might, of course, be constructed without employing a rod structure in association therewith. This cap might, moreover, be provided with an extension 27 as previously described.

Where, however, a rod 19 is employed, it is preferred as shown in Figs. 2 and 5 that the

rod be formed with a relatively extended portion or portions as at 30 and around which at the time of forming the cap, the moldable material is caused to extend. Thus, while in certain instances, it might be feasible to rely solely 5 upon frictional contact of the parts, there is provided by the construction just described—or its functional equivalent, an anchoring provision which will prevent completely any danger of 10 accidental displacement.

With structures such as the foregoing, it will be appreciated that among others the objects 15 as specifically aforesaid are achieved. Obviously, numerous changes in construction and rearrangements of the parts might be resorted to 20 without departing from the spirit of the invention as defined by the claims.

Having described my invention, what I claim 25 as new and desire to secure by Letters Patent is:

1. A closure including a cap, a plug secured 30 to the inner face of said cap, a bored extension forming a part of said cap and a swab mounting rod extending through said plug and having frictional engagement with said bore, the outer 35 end of said rod being split and extending angularly with respect to the rod body.

2. A closure including, in combination, a cap, an extension projecting from the inner face of 40 said cap and integral therewith, said extension being formed with a bore, a swab-mounting rod extending into said bore, an enlargement forming a part of said rod and within said bore to lock the same against displacement, and a plug 45 formed with an opening for the accommodation of said rod and secured to the inner face of said cap, said rod lying in contact with the face of said plug opening.

CHARLES M. VILLANYI.
